US00D996935S

(12) **United States Design Patent** (10) **Patent No.:** **US D996,935 S**
de Leon Capozza et al. (45) **Date of Patent:** **** Aug. 29, 2023**

(54) **BOTTLE**

(71) Applicant: **PepsiCo, Inc.**, Purchase, NY (US)

(72) Inventors: **Mirelle de Leon Capozza**, Newtown, CT (US); **Dmitriy Shmagin**, Palatine, IL (US); **Damien Z. Moyal**, Ypsilanti, MI (US); **John Siciliano**, Dexter, MI (US); **James M. Stelzer**, South Lyon, MI (US)

(73) Assignee: **PepsiCo, Inc.**, Purchase, NY (US)

(**) Term: **15 Years**

(21) Appl. No.: **29/859,082**

(22) Filed: **Nov. 7, 2022**

Related U.S. Application Data

(63) Continuation of application No. 29/794,419, filed on Jun. 11, 2021, now Pat. No. Des. 968,959.

(57) **CLAIM**

The ornamental design for a bottle, as shown and described.

DESCRIPTION

FIG. 1 is a top perspective view of a bottle showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the bottle that form no part of the claimed design.

The dot-dash broken lines in the figures show boundaries that form no part of the claimed design.

1 Claim, 7 Drawing Sheets
